DESIGN FOR A BAKING PAN

Joseph G. Jackson, Oak Park, Ill., assignor to The Edward Katzinger Company, Chicago, Ill., a corporation of Illinois

Application August 15, 1938, Serial No. 79,349

Term of patent 14 years

To all whom it may concern:

Be it known that I, Joseph G. Jackson, a citizen of the United States, residing at Oak Park, in the county of Cook and State of Illinois, have invented a new, original, and ornamental Design for a Baking Pan, of which the following is a specification, reference being had to the accompanying drawing, forming part thereof.

Fig. 1 is a top plan view of a baking pan, showing my new design.

Fig. 2 is a side elevational view thereof.

Fig. 3 is a fragmentary enlarged sectional view taken along line 3—3 of Fig. 1.

Fig. 4 is an enlarged fragmentary top perspective view of a corner portion of the baking pan.

Fig. 5 is an enlarged fragmentary bottom perspective view of the portion shown in Fig. 4.

I claim:

The ornamental design for a baking pan, as shown.

JOSEPH G. JACKSON,
